UNITED STATES PATENT OFFICE.

CARL KENDRICK MACFADDEN, OF DAYTONA BEACH, FLORIDA, ASSIGNOR TO MRS. C. K. MACFADDEN, PUBLICITY CHAIRMAN, WOMEN'S BRANCH HOOVER-FOR-PRESIDENT, ENGINEERS' NATIONAL COMMITTEE, OF NEW YORK, N. Y.

DESIGN FOR AN EMBLEM OR THE LIKE.

Application filed August 21, 1928. Serial No. 27,906. Term of patent 3½ years.

To all whom it may concern:

Be it known that I, CARL KENDRICK MACFADDEN, a citizen of the United States, and a resident of the city of Daytona Beach, in the county of Volusia and State of Florida, have invented the new, original, and ornamental Design for Emblems or the like, of which the following is a specification.

Reference is had to the accompanying drawings forming a part of the specification.

I claim:

The ornamental design for an emblem or the like, as shown.

Signed at city of New York in the county of New York and State of New York this 17th day of August, A. D. 1928.

CARL KENDRICK MACFADDEN.
